(57) **CLAIM**

The ornamental design for a magnetic phone grip as shown and described.

DESCRIPTION

FIG. 1 is a front perspective view of a magnetic phone grip showing my new design;

FIG. 2 is a rear perspective view thereof;

FIG. 3 is a front view thereof;

FIG. 4 is a rear view thereof; and,

FIG. 5 is a top view thereof.

Broken lines illustrate portions of the magnetic phone grip that form no part of the claimed design.
